UNITED STATES PATENT OFFICE.

HIRAM Q. HOOD, OF CARTHAGE, MISSOURI, ASSIGNOR, BY DIRECT AND MESNE ASSIGNMENTS, OF THREE-FOURTHS TO EZRA T. HARDAWAY, GEORGE BARNHART, E. J. HUNT, HENRY L. BRIGHT, AND ALVIN HATTEN, OF SAME PLACE, AND G. J. HUNT, OF LAMAR, MISSOURI.

STOVE.

SPECIFICATION forming part of Letters Patent No. 637,991, dated November 28, 1899.

Application filed May 25, 1899. Serial No. 718,136. (No model.)

To all whom it may concern:

Be it known that I, HIRAM Q. HOOD, a citizen of the United States, residing at Carthage, in the county of Jasper and State of Missouri, 5 have invented a new and useful Stove, of which the following is a specification.

This invention relates to heating-stoves; and the object of the invention is to provide a device of this character having a large extent of heating-surface and in which a high heat can be developed by the employment of a minimum amount of fuel, and the stove can be easily and inexpensively manufactured, and it is light, so that it can be easily moved 15 from place to place, and consists of the least possible number of parts capable of securing the above-mentioned results.

With these ends in view the invention consists in the novel combination of elements 20 and in the construction and arrangement of parts, which will be hereinafter fully described and claimed.

To enable others to understand the invention, I have illustrated the preferred embodiment thereof in the accompanying drawings, forming a part of the specification, and in which—

Figure 1 is a perspective view of a heating-stove constructed in accordance with my invention. Fig. 2 is a longitudinal central section of the same. Fig. 3 is a transverse sectional view. Fig. 4 is a perspective detail of parts broken away of the lower front corner of the stove and upon an enlarged scale and 35 showing the means for controlling the admission of air.

Similar characters denote like and corresponding parts in each of the several figures of the drawings.

40 The stove has a body portion which is designated in a general way by B, and which is mounted upon a base of any suitable kind, and it includes in its construction two end plates 2, which are formed, preferably, by casting, and an intermediate shell 3, which I prefer to make from sheet-steel or sheet-iron, thereby securing lightness. The shell is made

in one continuous piece, and it constitutes what might be termed the "sides," the "bottom," and the "top" of the stove, and the top 50 portion is curved to agree with the shape of the upper portions of the two parallel vertical end plates 2. The plates 2 are provided upon their insides with flanges 4, which can be made either separate from the respective parts or of continuous structure, and the shell 3 is disposed between and fits against the inside faces of the end plates and also against the flanges 4 thereon, and bolts, rivets, or other fastening devices serve to secure the 60 shell to the flanges at proper points.

The heat generated by the stove is obtained in part by the drum 5, which is made in the form of an open-ended cylinder, and which is supported by the end plates, and which 65 projects through circular openings formed in said plates below the top of the stove, and the hot air circulates around the drum for thoroughly and uniformly heating the same. The opposite ends of the drum are crimped 70 or turned over, as at 6, to fit against the outer faces of the end plates, thereby constituting a simple means for holding the drum against endwise movement.

The top of the stove has an opening 7 to receive the usual water-containing urn, and back of this opening the smoke-hole 8 is located and is surrounded by the collar 9, to which the lower end of the smoke-pipe can be coupled. 75

The forward plate 2 has a substantially rectangular aperture or opening 10, located below the heating-drum 5 and through which fuel can be introduced into the fire-pot, and this opening is normally closed by the door 12, 85 having the superposed parallel lugs 13 to receive the pivots 14, carried by the lugs 15, located one above the other on said forward plate, and the said door is provided with a projection 16 by which it can be opened and 90 closed, and it also has a latch 17, adapted to coöperate with the notched beveled catch on the end plate for the purpose of normally holding the door closed.

The stove has interiorly thereof the air-chambers 19, and these are located near the bottom thereof and are formed by portions of the stove-body and by the segmental longitudinal plates 20, located therein. The segmental or arched plates 20 fit against the end plates of the stove and are secured by some suitable fastening devices to the flanges 4 on said plates, and the chambers of which said 5 plates form a part are disposed in the lower opposite sides of the stove and the fire-pot is disposed between them, and they receive supplies of air through the openings 21 in the front end plate 2, and these openings may be of any number, and they may be covered by dampers, as 22, when occasion requires, slideable across the same and carried by the end plate, and the air which passes through these draft-openings 21 enters into 10 the air-chambers 19 and through the openings or perforations 23 formed in alignment in the segmental plates 19, and from thence passes into the fire-pot to promote combustion of the fuel therein, and the heated air will be 15 separated into two supplies which pass entirely around the heating-drum, and the latter is not only heated, but the body of the stove is also heated, and by reason of the large area subjected to the heat I am enabled to secure 20 efficient results.

The fire-pot includes in its construction two substantially U-shaped members 24, secured in longitudinal alignment upon the inner faces of the two end plates, and both of them are 25 flanged, as at 25, along their lower and side portions, and the side pieces 26 of the fire-pot, which are of substantially duplicate construction and are inclined, are secured to the side flanges of the two U-shaped members, and 30 they have lugs or ears 27 resting upon the horizontal flanged portion of said U-shaped members. The various sections constituting the framework of the fire-pot can be inserted in place through the fuel-opening 10 separately and can be secured together when in proper place, and the side pieces 26 have suitably-disposed openings or holes to receive the usual lining or fire-brick.

The grate constituting the bottom of the 35 fire-pot is denoted by 28, and it is represented as consisting of a longitudinal flat plate perforated to permit the escape of ashes and other waste products, and it has a transverse head 29, adapted to fit flatwise against the outer face of the front plate 2 when the grate 40 is in place, and this transverse head is provided with a handle 30, by which the grate can be operated, and it also serves to cover the opening 31, through which the grate is 45 introduced. The side pieces 26 of the fire-pot have inwardly-disposed aligned flanges 32, upon which the grate can slide as it is inserted in place and which serves also to support said grate.

The fire-pot is located above the two lines 50 of perforations 21 in the segmental plates 19

and between the same, so that the air which enters the air-chambers 19 through the openings 21 can act upon a considerable area of the fire, and the air passes upward heated 70 from the fire and is deflected to opposite sides of the heating-drum by means of the deflector-plate 33, which is of inverted segmental shape and which is separated from said drum and is located below the same. The deflector 75 plate or shield 33 separates the air into two parts and causes the same to circulate around the hot-air drum, and it also serves to prevent the application of too great heat directly to the under side of the drum, and it is made 80 substantially the same width as said drum and is flanged or crimped along its opposite end, as at 34, and the flanges or crimps are turned down and are suitably secured to the end plates 2.

The ashes and other refuse from the fire-pot are discharged into the ash-pan 35, which can be removed through the usual opening in the front of the stove.

A stove constructed as hereinbefore described is light, and it has a large area exposed to the heat, and the combustion can be promoted by reason of the distribution of the air-chambers, and the plates 20, serving as walls of said air-chambers, have openings disposed below the fire-pot, which serve to cool 90 the same with the incoming air, thereby prolonging the life of the fire-pot.

Changes in the form, proportion, size, and the minor details of construction within the 100 scope of appended claims may be resorted to without departing from the spirit or sacrificing any of the advantages of this invention.

Having thus described the invention, what I claim is—

1. In a stove, the combination with the base, of side and end plates secured thereto, one of said end plates having a flue-opening near the top and two door-openings and a grate-opening in the lower portion, the door-openings being located upon opposite sides of the grate-opening, and a series of draft-holes in each lower corner, the outer face of the plate being provided with door attachments adjacent to the door-openings and having its 115 inner face provided with a flange upon its top and side edges.

2. In a stove, the combination, with a base, of two end pieces secured thereto, each end piece being provided with a flange upon its 120 top and side edges and a circular flue-opening near the top, and one of the pieces being further provided with two door-openings and a grate-opening, said door-openings being upon opposite sides of the grate-opening, and a series of draft-openings in each lower corner, a shell secured to the end pieces and provided with a smoke-outlet, a flue secured at its ends in said flue-openings, a deflector below the flue, a fire-box below the deflector 125 and adjacent to one of the door-openings, a grate below the fire-box, one end of which

projects through the grate-opening and is provided with a flange and a handle, a curved perforated sheet at each side below the fire-box, an ash-pan upon the base, a door for each door-opening, and a damper for each series of draft-openings.

In testimony that I claim the foregoing as

my own I have hereto affixed my signature in the presence of two witnesses.

HIRAM Q. HOOD.
